UNITED STATES PATENT OFFICE.

BRUCE E. KIEFER AND BERNARD E. THAXTON, OF WASHINGTON, DISTRICT OF COLUMBIA.

VENDING MACHINE.

Application filed November 19, 1921. Serial No. 516,452.

To all whom it may concern:

Be it known that we, BRUCE E. KIEFER and BERNARD E. THAXTON, citizens of the United States, residing at Washington, in the District of Columbia, have invented certain new and useful Improvements in Vending Machines, of which the following is a specification.

Our invention relates to machines for vending merchandise and has for its primary object the provision of novel means whereby an article or a package may be delivered after a proper coin has been deposited within the machine. A further object of the invention is to provide a novel mechanism whereby, upon the deposit of the proper coin, the actuation of the apparatus will be possible. The invention also seeks to improve generally the construction and arrangement of the parts of a vending machine to the end that the operation may be simplified and the durability of the machine prolonged without any increase in the cost of production over machines now generally employed. The invention is illustrated in the accompanying drawings and consists in certain novel features which will be particularly pointed out in claims following a detailed description.

In the drawings—

Figure 1 is a perspective view of an apparatus embodying our invention;

Fig. 2 is a vertical longitudinal section of the same with parts in elevation;

Fig. 3 is a view partly in transverse section and partly in elevation;

Fig. 4 is a detail plan view of the operating mechanism;

Fig. 5 is an enlarged longitudinal section through the delivery chute and the parts co-operating therewith, showing the normal position of the parts;

Fig. 6 is a view similar to Fig. 5, but showing the position assumed by the several parts when an article is delivered;

Fig. 7 is an enlarged detail section of the coin-receiving and delivering disk;

Fig. 8 is a plan view of the coin disks;

Fig. 9 is a detail perspective view of the parts actuated immediately by the coin disks after proper coins have been delivered into the same.

In carrying out our invention, we em-

ploy a pedestal 1 which may be of the usual or any desired configuration and is preferably of metal so as to possess the desired strength and durability. Upon this pedestal, we secure a casing 2 which is likewise preferably of metal so as to possess the desired strength and durability. The casing is illustrated as provided with a hinged cover or top 3 equipped with a lock 4 whereby, after the articles or packages to be vended are placed within the casing, the cover may be locked thereto so as to prevent unwarranted access to the interior of the casing. The lock 4 may be of any well-known type and the shape of the casing and the disposition of the cover may be varied within wide limits without involving any departure from our invention. Within the casing 2 and upon the bottom plate of the same, we secure a post 5, upon the upper end of which is pivotally mounted the main operating lever 6, the said lever extending longitudinally of the casing and being provided at its rear end with a longitudinal slot 7 engaged by the wrist pin 8 of a crank 9 which is carried by a transverse rock shaft 10 journaled in standards 11 which are secured upon the bottom plate of the casing near the back wall thereof, as will be readily understood. The fulcrum or pivot 12 of the lever 6 is fitted in a vertical slot 13 in the post 5 and may, therefore, be adjusted vertically so that the throw of the lever may be nicely regulated and made to conform to the sizes of the coins with which it is intended to have the machine operated. The front shorter arm of the main lever is disposed immediately over the coin-receiving disks or carriers 14 which are secured upon the operating shaft 15 adjacent the front wall of the casing, said shaft being journaled in said front wall and in the post 5, as will be readily understood upon reference to Fig. 2. The operating shaft 15 projects through the front wall of the casing and is equipped with a knurled knob or other form of handle 16, as clearly shown, whereby the customer, after depositing the coin, may operate the shaft so as to actuate the delivering mechanism. Obviously, the shaft 15 is to be always turned in one direction and to prevent backward movement thereof, we provide a ratchet wheel 17 fixed upon the shaft immediately adjacent the

2
 front wall of the casing and engaged by a pawl 18 pivoted upon said wall or upon any other fixed part of the apparatus and held to the ratchet wheel by a spring 19 in an obvious manner. In the illustrated embodiment of our invention, two coin disks or carriers 14 are provided, but it will be understood that the number of coin disks will depend upon the price of the article or package to be vended and the number of coins which must be inserted in the machine to insure delivery. Leading from the exterior of the casing to the respective coin disks or carriers are coin chutes 20 which 10 communicate at their upper or outer ends with slots 21 formed in the casing to facilitate the insertion of the coins. The lower or inner ends of the coin chutes are disposed immediately adjacent the respective 20 coin disks or carriers so that coins deposited through the slots 21 will pass directly to the disks or carriers. In the periphery of each disk or coin carrier, we provide a circumferentially extending groove 22 which 25 gradually increases in depth rearwardly, in the direction of rotation of the disk, as clearly shown in Fig. 7, whereby a coin, indicated at 23, dropping upon the periphery of the disk will be positively engaged and guided to the coin pocket or holder 24 with which the disk or carrier is equipped. While the coin pocket may be simply a recess formed in the disk, as shown at 25, we prefer to provide interchangeable holders 30 35 40 45 50 55 60 65 70 75 80 85 90 95 100 105 110 115 120 125 130 which may conveniently be metallic blocks of proper shape and dimensions to fit within the recesses 25 and having bores 26 therethrough of proper width to receive the coins which will permit the operation of the machine. The front end wall of the holder 24 is notched, as shown at 27, so that, when the holder is placed in the recess 25, the notch 27 will form a continuation of the groove 22 to permit the coin to enter the holder, and, to support the coin in the holder in the proper position to actuate the main lever 6, shoulders 28 are formed on the inner surfaces of the front and rear end walls of the holders upon which the coin will rest, as clearly shown in Fig. 7. The bore 26 extends entirely through the holder so that, if a coin smaller than the designated coin is inserted, it will drop to the bottom of the holder and upon rotation of the disk or carrier will pass under the lever 6 without actuating the same and, as the rotation of the disk continues, will drop through the outer end of the holder and be caught in the coin box which may be of any desired form and located at a proper point within the casing to receive the coins from the coin carriers or disks. Inasmuch as the particular form or arrangement of the coin box is not essential to our invention, we have 80 85 90 95 100 105 110 115 120 125 130 omitted the illustration of the same from the

drawings in order than the parts appearing in the drawings may be shown more clearly. The coin holders 24 conform to the recesses 25 in their outline and dimensions so as to fit snugly therein and they are adjustably held within the recesses by set screws 29 which are inserted in the bodies of the disks upon chords of the same so that their inner ends will bind upon the rear end walls of the holders, as clearly shown in Fig. 7. This arrangement permits us to adjust the holders radially of the coin carriers so that the proper engagement of the coins with the lever 6 will be effected. Upon the rock shaft 10 between the ends 80 thereof, we secure a pusher or crank 30 which bears upon the rear end of a plunger rod 31 extending forwardly and slidably supported in a bearing 32 at the upper end of a post or standard 33 secured upon the bottom plate of the casing 2, as shown and as will be readily understood. The rear end of the bearing 32 is counter-bored, as shown at 34, so as to accommodate the front end of a spring 35 which is coiled around the plunger rod 31 between the forward end of the counter-bore 34 and an abutment 36 secured upon the plunger rod. The spring, by its expansion, serves to hold the plunger rod in constant engagement with the pusher or crank 30 so that the plunger rod will respond instantly to the movements of the pusher. To the front end of the plunger rod 31, the plunger 37 is secured and this plunger is mounted to slide upon a platform 38 and between guides 39 at the rear corners of the said platform, the said platform being secured to and extending between standards 40 erected upon the bottom plate of the casing 2 and having their upper ends connected by brackets 41 which are so formed as to present internal shoulders 42 whereby they are adapted to support a container 43 in which the articles or packages to be vended may be placed in superposed relation. Our machine is intended more particularly for vending cigars, cigarettes, wrapped chocolate bars, and similar merchandise. In the present instance, we have illustrated cigars 44 which are supplied in small boxes so that only one layer or row of cigars will be furnished in each box. In fitting such boxed cigars in the apparatus to be vended, we remove one side wall of the box and then place the box between the brackets 41 so that the open side thereof will become the bottom and the cigars may then gravitate to the platform 38. The front bracket 41 is of such proportions and so arranged that its lower edge will be spaced above the platform 38 a distance sufficient to permit the passage of only a single cigar. This single cigar will be pushed through the space or opening between the bracket and the platform by the action of the plunger 37 and the plunger 130

will be equal in height to the diameter of the cigar so that the second cigar will be supported by the plunger when the latter is in the delivery position, as clearly shown in Fig. 6. As the plunger is withdrawn, however, the support for the cigars will be removed and the entire column will drop so that the lowest cigar will then rest upon the platform 38. Hinged to the front edge of the platform 38 is a baffle or trap door 45 which normally extends across or nearly across the delivery chute 46 which extends from the bracket 41 to the bottom of the casing 2 and there communicates with a holder or receptacle 47 depending from the bottom of the casing and having its front side open, as shown at 48, to permit the customer to remove the delivered cigar. As the plunger 37 moves forward to deliver the purchased cigar, the baffle or trap door will be swung downwardly to the position shown in Fig. 6 and to accomplish this movement of the baffle, we secure to the under side thereof a bracket 49 which is in the form of a slotted 25 arcuate arm extending downwardly and forwardly from the baffle. The slot in this arm is engaged by a pin 50 at the front end of a lever 51 which is fulcrumed between its ends, as at 52, upon a post 53 erected on the bottom plate of the casing 2, the rear end of the said lever being extended upwardly from the fulcrum and carrying a rearwardly extending knuckle member 54. Pivoted in the member 54 is a mating knuckle member 55 which is connected by a link 56 with a third knuckle member 57, the said knuckle 57 being pivotally fitted within a mating knuckle member 58 which is carried by the lower end of a goose neck pusher or finger 59 secured to and depending from the plunger rod 31. The knuckles and the link 56 connecting the same, together with the lever 51 constitute a toggle connection between the pusher finger 59 and the slotted bracket 49, the operation of which will be readily understood upon reference to Figs. 5 and 6 of the drawings. As the plunger moves forwardly, the pusher 59 exerts a forward pressure upon the knuckles and the connection between the same which is converted into a rocking movement of the lever 51, the pin 50 carried by said lever being thereby swung downwardly and forwardly in the slot of the bracket 59 so as to exert a downward pull thereon and swing the baffle plate 45 from the position shown in Fig. 5 to that shown in Fig. 6 so that the obstruction in the delivery tube will be removed and the cigar or other article may roll through the tube to the receptacle or holder 47. Of course, upon the reverse movement of the plunger, the baffle will be returned to its normal position, and it will be understood, of course, that the slot in the bracket 49 is curved eccentric to the lever 51 in order that the desired pushing or pulling action of the lever upon the bracket will be obtained.

When the price of the article to be vended may be represented by a single coin, such as a dime, one of the coin slots 21 may be closed by a suitable plug or the coin disk or carrier in alignment with said slot may be removed. The holder 24 in the coin disk or carrier which is to be utilized as the actuating agent is adjusted radially of the carrier so that the coin in the holder will project beyond the periphery of the carrier the distance necessary to impart to the main lever 6 sufficient vibration to obtain the desired results. When the price of the article to be vended requires the use of two coins, as, for instance, when the article is to be sold for fifteen cents, and it is necessary to insert a dime and a nickel, two coin carriers are, of course, employed. These carriers will be so arranged that the smaller coin will impart an initial movement to the lever 6 while the larger coin will travel slightly in rear of the smaller coin and will impart a greater movement to the lever. When the parts are properly adjusted, the initial movement given by the coin of lesser diameter will be insufficient to impart a complete working stroke to the plunger and if the initial movement be not given to the lever, the coin of greater diameter will impinge against the side of the lever and stop the movement of the coin carrier. Consequently, both coins must be inserted as neither alone will effect operation of the delivery mechanism. These relative working positions of the coins will be readily understood upon reference to Figs. 4 and 8 of the drawings. As the front end of the lever 6 is raised by the coins riding under the same, the rear end of the lever will, of course, be depressed and will swing the crank 9 downwardly so that the shaft 10 will be rocked and the pusher 30 swung forwardly. The plunger rod and the parts attached thereto will be moved forwardly by the action of the pusher or crank 30 against the tension of the spring 35 which will be compressed and will be housed within the counterbored end of the bearing 32 while in the compressed state. The pusher finger 59 and the plunger 37 will, likewise, move forwardly and the purchased article will be delivered, as previously described. The rotation of the coin disks is effected by the purchaser rotating the knob or handle 16 in an obvious manner and the purchaser will, of course, continue the rotation until the purchased article appears at the opening 48. The time required for the article to appear at the opening 48 will define such an interval that the rotation of the coin carriers during that interval will bring the coins to a point below the horizontal diameter of the carriers, whereupon the coins will, of course, roll

from the carriers and be caught in the coin box. It will be readily seen upon reference to Fig. 5 that access to the container through the opening 48 is prevented by the normal 5 position of the baffle plate 45 and as backward rotation of the coin carriers is prevented by the ratchet 17 and the pawl engaging the same, the manipulation of the mechanism to cause a second actuation of 10 the main lever 6 by a single coin will be prevented. It will be readily noted that we have provided a very simple and compactly arranged mechanism which will be positive in its action and by reason of its simplicity 15 20 25 will not be apt to get out of order. The longitudinal slot 7 in the main lever 6 accommodates the varying angular relation of the lever to the crank 9 and the slot 13 in the post 5 permits the fulcrum of said lever to be adjusted vertically so that the action may be very accurately regulated. This adjustment of the fulcrum of the main lever will be desirable at times in order to obtain the proper movement of the plunger to effect delivery of the articles to be vended but otherwise the only change necessary in the operating mechanism to permit the vending of various articles is to substitute one container for another. The various posts or standards which are utilized as supports for the working parts may be of any preferred or convenient construction and the brackets 41 which support the article container may be removable so that brackets of various outlines may be interchangeably used.

The front of the casing 2 is provided with a glazed view opening 60 so that an intending purchaser will be enabled to inform himself whether or not the container is empty.

40 Having thus described the invention, what is claimed as new is:

1. In a vending machine, the combination of means for supporting articles to be vended, means for delivering one of the articles, 45 a lever operatively connected with said delivering means, a plurality of concentric coin carriers disposed below one end of said lever and transversely thereto to receive coins in stepped relation, and means for simultaneously actuating said coin carriers whereby coins deposited therein will be successively caused to impinge upon and actuate the lever.

2. In a vending machine, the combination 55 of article-delivery means, a lever arranged to actuate said article-delivery means, a coin carrier disposed below one end of the said lever, and a coin holder fitted in the coin carrier and adjustable radially therein

whereby a coin supported in the holder may 60 project more or less from the carrier and impinge against the lever to actuate the same.

3. In a vending machine, the combination of article-delivery means, a lever to actuate said means, a rotatable coin-carrying disk disposed transversely below the lever and provided in its periphery with a circumferentially extending groove gradually increasing in depth in the direction of rotation of the disk, a coin holder adjustable radially in the disk in alignment with said groove and communicating therewith, said coin holder being constructed to engage both faces of a coin and support the same 75 edgewise whereby the coin will ride across the under side of the lever to actuate the same, and a coin chute arranged above the coin-carrying disk and in vertical alignment with the said circumferentially extending groove.

4. In a vending machine, the combination of a coin carrier provided with a radial recess opening through its surface, and a coin holder fitting snugly in said recess and having a coin-receiving bore opening through both its ends, the front and rear walls of said bore being provided with shoulders whereby to support a coin.

5. In a vending machine, the combination of article-delivery means, a rock shaft arranged transversely to said means and arranged to actuate the same, an upstanding crank on the rock shaft, a lever fulcrumed between its ends and having its 95 rear end engaged with the crank on the rock shaft, the lever and the article-delivery means being arranged side by side, a rotatable coin carrier arranged below the front end of said lever and transversely thereto 100 whereby a coin in the carrier will be caused to ride across the under side of the lever to actuate the same, and a coin chute above and leading to said carrier.

6. In a vending machine, the combination of article-delivery means, a post, a lever fulcrumed between its ends upon said post, the fulcrum being vertically adjustable, operative connections between the rear end of the lever and the article-delivered means, and 110 a coin carrier arranged below the front end of the lever and adapted to actuate the lever through an inserted coin.

In testimony whereof we affix our signatures.

BRUCE E. KIEFER. [L.S.]
BERNARD E. THAXTON. [L.S.]
